RECHARGING BASE FOR BATTERY OPERATED TOOTHBRUSH

LaVern G. Soper, Eau Claire, Wis., assignor to National
Presto Industries, Inc., Eau Claire, Wis., a corporation
of Wisconsin

Filed June 11, 1969, Ser. No. 17,634

Term of patent 14 years

Int. Cl. D4—02

U.S. Cl. D4—16

Fig. 1

Fig. 5

Fig. 6

Fig. 2.

Fig. 3.

Fig. 4.

FIG. 1 is a perspective view of a recharging base for a battery operated toothbrush, showing my new design; FIG. 2 is a front elevational view of the recharging base;

FIG. 3 is an elevational view of one side of the recharging base, the opposite side being substantially a mirror image thereof;

FIG. 4 is a rear elevational view of the recharging base;

FIG. 5 is a top plan view of the recharging base; and FIG. 6 is a bottom plan view of the recharging base.

I claim:

The ornamental design for a recharging base for a battery operated toothbrush, substantially as shown and described.
